Primary Examiner — Clare E Heflin(74) *Attorney, Agent, or Firm* — McCracken & Gillen LLC(57) **CLAIM**

The ornamental design for the luminaire, as shown and described.

DESCRIPTION

FIG. 1 is an isometric view of a top, front, and left side of an ornamental design of a luminaire;

FIG. 2 is a front elevational view of the luminaire of FIG. 1;

FIG. 3 is a top plan view of the luminaire of FIG. 1;

FIG. 4 is a left side elevational view of the luminaire of FIG. 1;

FIG. 5 is a right side elevational view of the luminaire of FIG. 1;

FIG. 6 is a bottom plan view of the luminaire of FIG. 1;

FIG. 7 is a rear elevational view of the luminaire of FIG. 1; and,

FIG. 8 is an isometric view of a bottom, front, and left side of the luminaire of FIG. 1.

The broken lines (where present) in all FIGS. illustrate portions of the luminaire that form no part of the claimed design.

1 Claim, 5 Drawing Sheets(56)
